INVENTOR:
WILLIAM S. SUTTON

BY Wm. D. Aldcock,
HIS ATTORNEYS.

UNITED STATES PATENT OFFICE.

WILLIAM S. SUTTON, OF BELVIDERE, ILLINOIS.

FISH-REEL.

SPECIFICATION forming part of Letters Patent No. 693,459, dated February 18, 1902.

Application filed August 27, 1900. Serial No. 28,096. (No model.)

To all whom it may concern:

Be it known that I, WILLIAM S. SUTTON, a citizen of the United States, residing in Belvidere, in the county of Boone and State of Illinois, have invented a new and useful Improvement in Fish-Reels, of which the following is a specification.

This invention relates to an improvement in the construction of fish-reels; and its nature and object will appear more fully from the following specification, in connection with the accompanying drawings, in which—

Figure 1 is a top or plan view of my improved reel. Fig. 2 is a side elevation of the same. Figs. 3 and 4 are a section taken on the lines 3'4 of Fig. 2, this section being made upon a larger scale than said former figures. Fig. 5 is a perspective of the open end of the reel-frame upon the same scale as Fig. 1; and Fig. 6 is an interior face view of the removable head, also upon the same scale as Figs. 1 and 2. Figs. 7, 8, 9, 10, 11, and 12, upon the same scale as Figs. 3 and 4, represent details of the mechanism.

The reel, as shown in said drawings, is made of the usual approved form, consisting of the barrel A and convex end disks A' A'.

B is the axle of the reel, the ends of which at b are coned. Attached to this axle is the pinion C.

D is the crank-axle, coned at d, and E is the usual crank-handle connected to said crank-shaft D. Attached to said crank-shaft is the usual gear-wheel F, meshing with the pinion C and multiplying the revolutions of the crank-shaft at the reel-shaft. The two bearings for the reel-shaft and the two bearings for the crank-shaft are each ball-bearings, the balls being shown at G, and these balls bear in each case upon the coned portions of the shaft, so that whatever the strain or thrust may be or become in action the movement of the shafts is frictionless, or at least as frictionless as a ball-bearing makes it. This frictionless movement of the bearings throughout makes the reel a very free running one and is a great advantage in casting.

H H' H² H³ are the cupped ball-seats, in the cup of which the balls G are placed and held in place by a ring h, which may be an ordinary split-spring ring, as shown in Fig. 12, or may be a screw-threaded ring h, as

shown in respect to the large cup H². In the structure shown in the drawings the spring form of ring is employed on three of the bearings H H' H³ and the screw form of ring is employed on the larger bearing H². In each case the cup is externally circular and screw-threaded for the purpose of securing them to the cases or frame of the reel. The heads of the reel-case are each provided with a hub J, internally screw-threaded, and the cups H and H' are screwed into these hubs and adjusted by means of said screw-threads to proper position with reference to the ends of the shaft. For convenience in turning these screw-threaded cups into place the cup is made with a projecting neck h', slotted at the ends h² to receive a screw-driver, and to secure the cups in place when adjusted the washer h³, having a projection h⁴, is slipped over the neck h' of the cup, the interior of the hub being grooved to receive said projection h⁴; and a hollow jam-nut h⁵ (shown in Figs. 7 and 8) is screwed down firmly upon the washer, locking the cup firmly in place, the friction of the stationary washer h³ preventing the cup from loosening by turning. The large cup H² on the outer end of the crank-shaft may be constructed precisely in the manner above described—that is to say, with a hub on the casing; but I have found it more convenient in the manufacture to make a variation—that is to say, instead of having a hub on the casing in this instance I make an aperture through the casing and provide the inner end of the cup H² with a collar h⁶ and secure the cup to the casing by means of an external ring-nut h⁷. This construction enables me to make the crank-shaft adjustable to and from the reel-shaft by slotting the aperture in the casing through which the neck of the cup passes. The inner bearing of the crank-shaft is carried in a stirrup-frame K, secured to the casing by screws K', and the apertures in the casing through which these screws K' pass to the outside should, in like manner, be slotted to permit this end of the shaft to be subjected to and from the reel-shaft to compensate for wear in the gearing.

In the form of bearings shown the balls are locked in the cups and the axles may all be removed readily and replaced without disar-

ranging the bearing. This is a great convenience in such a structure as a fish-reel.

It will be noted that the bearings of the two ends of the reel-shaft are of such nature that the axle does not penetrate far into the bearings and being cone-shaped at the ends is self-centering upon the balls. This feature enables me to readily make the device separable, so that the reel itself, with its axle and the pinion thereon, may be bodily removed from the casing and replaced with the greatest facility, and this feature is an advantage and convenience to the user, for, as is well known, sometimes the reel overruns or the wet line from other cause becomes entangled or inwound on the body of the reel. In such case the whole reel can be bodily removed from the casing in my construction and the trouble removed without difficulty and the reel replaced in running order, and in the present structure to accomplish this it is only necessary to make one of the heads of the casing removable endwise. In the structure shown this removability is given to the head M—the one to which is connected the crank-shaft. At this end of the reel-frame the framework is extended in the form of a cylindrical collar N (shown at Fig. 5) and provided with bayonet-slots n. The head M is provided with a flange m to slip over the collar N, and this flange m has internally-projecting pins m' to engage the bayonet-catches. The head M is applied to the frame by slipping it on endwise and turning it to lock the bayonet-joint, as will be readily understood. To prevent accidental unlocking, the collar N has a spring n', provided at its free end with a small round-headed pin n², which projects through the collar N, and when the head M is in place projects through an aperture in the flange m of said head, thus locking the two parts together with sufficient firmness to prevent rotary disengagement. When the head M is to be removed, this spring-pin n² is depressed by the thumb, and the bayonet-joint may be disengaged. When the head M is thus removed, the reel may be slipped out endwise, there being nothing to prevent its ready removal as a whole, carrying with it its axle and the pinion thereon, and in like manner said reel can be

replaced, the conical end of the axle readily entering the ball-bearing and centering itself, and the ball-bearing on the head M readily centering itself upon the other end of the axle and the pinion and gear-wheel as readily sliding into engagement. 55

I claim—

1. The fish-reel provided with ball-bearings at each end of the reel-shaft and ball-bearings at each end of the crank-shaft, the crank-shaft and its bearings and one of the bearings of the reel-shaft being connected to a removable head, which in turn is connected to the framework of the reel by means of a bayonet-joint formed in the cylindrical part of the head, said removable head being furnished with a spring-detent, all substantially as specified, whereby said head may be easily and quickly removed and applied to said framework, and will be brought to a positive position when applied, and will be locked by the detent against accidental displacement. 65

2. The fish-reel provided with ball-bearings on the reel-shaft and ball-bearings on the crank-shaft and having a removable head which carries one of the bearings of the reel-shaft and also the crank-shaft and its bearings, the ball-cup of the crank-shaft bearings being provided with an internal collar and an external ring-nut between which the balls are held, substantially as specified. 75

3. In a ball-bearing fish-reel having a removable head to which is attached one of the reel-shaft bearings and upon which is attached a crank-shaft and its bearing, and the gearing on the crank-shaft, the ball-cup for the outer bearing of the crank-shaft provided with an internal collar and an external ring-nut between which and the collar the head is clamped for securing said bearing to the head, substantially as specified. 85

4. The fish-reel provided with a removable cylindrical head fitting on a cylindrical part and provided with a bayonet-joint between the reel and the head, and a spring-detent between said head and reel, substantially as specified. 95
